POWER TRANSMITTING MECHANISM

Filed Sept. 17, 1930

Charles W. H. Doubler

UNITED STATES PATENT OFFICE

CHARLES W. H'DOUBLER, OF SPRINGFIELD, MISSOURI

POWER TRANSMITTING MECHANISM

Application filed September 17, 1930. Serial No. 482,555.

This invention relates in general to improvements in power transmitting mechanisms, and relates more specifically to improved mechanism especially applicable to 5 electrically operated sewing machines, the present invention constituting an improvement upon certain features of the invention covered by my former Patent No. 1,472,588 granted October 30, 1923 relating to Electrically driven sewing machines.

A general object of the invention is to provide improved power transmitting mechanism which is simple and compact in construction, and which is moreover highly efficient in operation. It is also a general object of the invention to provide improved motion transfer mechanism which is especially applicable to power driven sewing machines or the like.

While some of the prior electrically operated sewing machines are relatively efficient in operation, the motor is usually so disposed that the general appearance of these machines is unsightly and distorted, due to having the 25 motor attached as an appendage. Aside from this defect all sewing machines now on the market have an excessive number of moving parts exposed at the exterior of the machine.

It is, therefore, one of the more specific objects of the present invention to overcome 30 these objectionable features of the prior machines and to provide an electrically operated sewing machine of unitary structure with the motor concealed entirely within the confines 35 of the frame.

A further specific object of the invention is to provide a power operated sewing machine having concealed and readily manipulable means for operating the bobbin 40 rewinding spindle.

Another specific object of this invention is to provide a means for permitting substantial concealment of the bobbin rewind device of a sewing machine within the frame when 45 not in use.

Still another specific object of the invention is to provide a bobbin that will automatically take the thread, without the necessity of first starting the thread by hand winding as in the prior machines.

A further specific object of the invention is to provide improved mechanism for driving and for effecting manipulation of devices for winding cord or thread upon a spool, reel, 55 bobbin or the like.

With the above and other objects in view, which will become apparent as the description proceeds, the present invention comprises the improved power transmitting mechanism especially applicable to electrically operated sewing machines substantially 60 as set forth in the claims and all equivalents thereof.

In the accompanying drawing, the same reference characters designate the same or 65 similar parts in the several views:

Fig. 1 is a side elevation of that portion of the improved electrically operated sewing machine which relates to the present invention, parts having been broken away to more 70 clearly show the interior structure;

Fig. 2 is a fragmentary view looking at the bottom of the machine with a portion of the bottom cover broken away to more clearly show the interior structure, the view being 75 taken at right angles to that shown in Fig. 1; and

Fig. 3 is a side elevation of the improved bobbin.

Referring to the drawing, the numeral 4 80 indicates the frame of a sewing machine.

An electric motor 5 is positioned centrally within the lower portion of the frame 4, and surrounds a horizontal drive shaft 6, the field portion 7 of the motor being supported concentrically of the shaft, between two lugs 8 85 by means of screws 9.

The armature 10 of the motor 5 is supported upon a tubular shaft 11 which is provided at its forward end with an annular groove 12 90 and a clutch member 13, this tubular shaft 11 being journaled directly upon the drive shaft 6.

A corresponding clutch member 13' is also 95 journaled on said drive shaft adjacent to and suitably disposed for engagement with the clutch member 13, the clutch member 13' being provided with an oil throwing disk 14 and with an integral tubular sleeve 15 which 100 supports a pinion 16. The pinion 16 meshes

with a gear wheel 17 supported upon an integral sleeve extension 18' of a pinion 18 which is journaled upon a counter shaft 19. The pinion 18 meshes with another gear wheel 20 which is attached to the drive shaft 6 by a pin 21 or in any other suitable manner.

It now becomes apparent that when the two clutch members just described are engaged, as shown in the drawing, rotary motion may 10 be transmitted from the armature 10 to the drive shaft 6 at a predetermined lesser speed of rotation than that of the rotary speed of the armature, and that the armature and the shaft will travel in the same direction of rotation with minimum friction losses.

The armature 10 of the motor is also provided with a commutator 22 in which the segments are elongated to permit the armature to be slid back and forth on the drive 20 shaft 6 without interrupting contact with the carbon brushes 23 supported in the brush holders 24. These brush holders 24 are retained in slotted lugs 25 by means of screws 26, contact between said brushes and the field 25 coils 27 being had through the medium of metal clips 28 which are gripped by the metallic portions of the brush holders 24 and are attached to the field lead wires 29.

Another clutch member 30 is secured to 30 the commutator end of the armature so as to cooperate with a corresponding clutch member 31 provided with an extending flange portion 31' mounted in any suitable manner on the front side of a pinion 32. The pinion 32 is slidably supported upon the drive shaft 6 and meshes with a gear wheel 33 secured to a shouldered shaft 34. The shaft 34 is journaled in the frame 4 and has a split, resilient spindle-like end 34' protruding at the 40 back of the standard portion of the frame 4. The split end 34' of the spindle is adapted to drivingly engage the bobbin 35 by yielding lateral pressure of the bifurcations, during winding of the bobbin.

Owing to the confined location of the winding spindle in the present invention, it would be difficult to start a bobbin preparatory to winding, by the usual method of first giving the thread a few turns around the bobbin 50 stem by hand in order to give the thread a grip on said stem. A short slot 35' is therefore provided in the rim of one side of each of the bobbins 35 to automatically engage the thread as will be hereinafter explained, the 55 moment the bobbin is rotated.

To facilitate winding of the bobbins, a headed pin 36 is provided for conveniently supporting the thread supply spool. The spool supporting pin 36 may be mounted in 60 the wall of the standard portion of the frame 4, in such manner that it may be easily pressed back into the standard when not in use, or the pin may be readily withdrawn when required, being restrained against complete 65 withdrawal by a small peg 37 extending

through the pin near its inside extremity. A tension thread guide is also provided, this guide consisting of two flanged disks 38 and 38' loosely mounted on a headed pin 39 supported by a lug 40 at the back corner of the 70 bed-plate portion of the frame 4. Tension is imparted to the thread passing over the guide, by means of a light coil spring 41 encircling the headed pin 39 and yieldingly engaging the lug 40 and the inside disk 38'. 75

It should now be apparent that in order to operate the bobbin winding spindle 34', it is only necessary to shift the connections from the clutch in front of the motor to the clutch at the rear thereof, and to accomplish this, a properly formed lever 42 is provided. The lever 42 is pivoted to the frame by a shouldered screw 43 and is provided with a pin 44 rigidly supported and so positioned as to centrally engage the annular groove 12 in the end of the tubular armature shaft 11. The arrangement is such that the lever 42 may be operated from the top of the bed or sewing plate by means of an upright handle 45 which is supported on the disengaged end of said lever 42, the handle being just long enough to penetrate the sewing plate through a slot 46 provided in said plate. Throwing the lever 42 back, slides the armature backward through the medium of the pin 44, and thereby disengages the front clutch members and engages those clutch elements which operate the bobbin winding device at the rear, and, of course, vice versa.

As a means for yieldingly supporting the lever 42 and to hold either predetermined set of clutch members in engaged position, a flat spring 47 is secured to the frame by a screw 48; said spring being formed and positioned to produce yielding pressure against the lever. The spring 47 is adjustable as to pressure, by means of an adjustment screw 49; and the spring is also provided with two slight V-shaped indentures 47' running crosswise thereof and so positioned that the two angular detents formed by the said indentures on the opposite side of the spring will simultaneously yieldingly engage the two edges of the lever.

The well known tendency of the magnetic field portion of a motor to draw the armature toward its true magnetic center relative to the field, assures positive functioning of the forward clutch members 13 and 13' so that irrespective of whether the cooperating jaws 115 on the clutch members interlock at the time the lever 42 is thrown forward, these jaws will be forced into interlocking position by the magnetic action when the armature begins to rotate, and thus pull the end of the lever 42 into the yieldingly retained position between the detents on the spring 47 as shown in Fig. 2.

To insure similar functioning of the rear clutch members 30 and 31, a short coil spring 130

50 is introduced around the shaft 6 between and abutting a bearing 51 and a flange 52. The flange 52 is secured to the pinion 32 in any suitable manner and cooperates with the 5 flange portion 31' to retain the pinion, which is loosely journaled on the shaft 6, always in mesh with the gear wheel 33. When a rearward pressure is brought to bear against the lever handle 45 the yielding resistance of the 10 spring 47 will be overcome, and the armature will slide rearwardly upon the shaft 6 by means of the pin 44 engaging the annular groove 12. This rearward shifting of the armature of the motor will disconnect the 15 front set of clutch members 13, 13' and will cause the clutch member 30 to be pressed into engagement with the clutch member 31, thereby compressing the coil spring 50 so that in case the detents of the clutch members 20 should not exactly register when brought together, the coil spring will positively establish a driving connection when the armature is rotated.

Winding of a bobbin is accomplished by 25 first throwing the lever 42 backwardly in the manner just described, thereby interrupting the driving connection with the sewing mechanism, and, by the same act, establishing a driving connection with the bobbin 30 winding device. The headed pin is then drawn outwardly to its extreme position, and the spool of thread is slipped onto the pin. The loose end of the thread is then drawn around the pin portion of the thread guide 35 between the two disks 38, 38' and back under the stem of the bobbin 35 and held upright and rearwardly by hand, to cause the thread to bear against the edge of the rear or outside flange of the bobbin. The motor is then 40 started and the first revolution of bobbin causes the thread to enter the peripheral slot and thereby causes the bobbin to begin winding.

When the bobbin has been sufficiently 45 wound or supplied with thread, the thread may be severed and the bobbin freely removed from the bifurcated end of the shaft 34, the resilient bifurcations of which provide a frictional driving connection during the winding 50 operation. After the spool of thread has been removed from the pin 36, this pin may be pushed into the frame 4, thus concealing the pin. The lever 42 may then be shifted forwardly to re-establish the driving connection 55 between the forward clutch members 13, 13' and to simultaneously interrupt the driving connection between the rear clutch members 30, 31.

From the foregoing description, it will be 60 apparent that the present improvement provides an extremely simple, compact and conveniently operable power transmitting mechanism for imparting motion from the driving motor to the bobbin winding device 65 of a sewing machine. The formation of the

bobbin 35 with a peripheral notch 35' in one of the side flanges thereof, provides simple and effective means for starting the thread winding, and the improved guide wheel insures uniform distribution of the thread upon 70 the bobbin hub.

It should be understood that it is not desired to limit the invention to the exact details of construction herein shown and described, for various modifications within the 75 scope of the appended claims, may occur to persons skilled in the art.

What I claim as my invention is:

1. In combination, a driven shaft, a motor for driving said shaft, said motor comprising 80 an armature surrounding and movable along said shaft, means when the armature is in one position for transmitting motion from said armature to said shaft and rotating said shaft at a certain speed of rotation, means journaled on said shaft and when the armature is in another position for alternately transmitting motion from said armature to another source of power utilization at a different speed of rotation, and means for moving the 85 armature longitudinally on the shaft.

2. In combination, a driven shaft, a motor for driving said shaft, said motor comprising an armature surrounding and movable along said shaft, means at one end of said 90 armature and when the armature is in one position for transmitting motion therefrom to said shaft, means journaled on said shaft at the opposite end of said armature and when the armature is in another position for alternately transmitting motion from said armature to another source of power utilization, and means for moving the armature longitudinally on the shaft.

3. In combination, a driven shaft, a motor for driving said shaft, said motor comprising an armature movable along said shaft, means for transmitting motion from said armature and when the armature is in one position to said shaft at lower speed than that 100 of said armature, means disposed concentrically of said shaft and when the armature is in another position for alternately transmitting motion at another speed than that of said armature to another source of power utilization, and means for moving the armature longitudinally on the shaft.

4. In combination, a driven shaft, a motor for driving said shaft, said motor comprising an armature embracing said shaft and movable longitudinally thereon, means including a clutch for transmitting motion from said armature to said shaft when the armature is in one position, means including another clutch for alternately transmitting motion from said armature to another source of power utilization when the armature is in another position, and common means for controlling the movement of the armature and the operation of both of said clutches.

5. In combination, a driven shaft, a motor for driving said shaft, said motor comprising an armature embracing and movable along said shaft, means including a clutch
5 for transmitting motion from said armature to said shaft, means including another clutch for alternately transmitting motion from said armature to another source of power utilization, and a lever for moving said armature
10 to control the actuation of both of said clutches.
6. In combination, a driven shaft, a motor for driving said shaft, said motor comprising an armature surrounding and movable along
15 said shaft, means for transmitting motion from said armature to said shaft, means for alternately transmitting motion from said armature to another source of power utilization, a lever for moving said armature along
20 said shaft, and means for utilizing the magnetic field of said motor to place said lever in a predetermined position.
7. In combination, a driven shaft, a motor for driving said shaft, said motor comprising an armature movable along said shaft, means at one end of said armature for transmitting motion therefrom to said shaft when the armature is in one position, and a resiliently restrained clutch adjacent the opposite end of said armature for alternately transmitting motion from said armature to another source of power utilization when the motor is in another position, and means for moving the armature longitudinally on said
35 shaft.
8. In combination, a driven shaft, a motor for driving said shaft, said motor comprising an armature surrounding and longitudinally movable on the shaft, means when the
40 armature is in one position for transmitting motion from the armature to the shaft to cause said shaft to rotate at a slower rate of speed than the armature, means when the armature is in another position and the shaft
45 is at rest for transmitting motion to another source of power utilization, and means for moving the armature longitudinally on said shaft.
9. In combination, a driven shaft, a sleeve
50 journaled and longitudinally movable on said shaft, a motor for driving said shaft comprising an armature mounted on the sleeve and movable therewith, means co-acting with one end portion of the sleeve when in one
55 position on the shaft for transmitting motion from the armature to the shaft, other means co-acting with the opposite end portion of the sleeve when in another position on the shaft for transmitting motion from the
60 armature to another source of power utilization, and means for moving the sleeve and the armature longitudinally on the shaft.

In testimony whereof, I affix my signature,
